(57) **CLAIM**

The ornamental design for a suspended lightguide luminaire with linear sound baffles, as shown and described.

DESCRIPTION

FIG. 1 is a bottom perspective view of a suspended lightguide luminaire with linear sound baffles, showing our new design;

FIG. 2 is a top perspective view thereof;

FIG. 3 is a bottom view thereof;

FIG. 4 is a top view thereof;

FIG. 5 is a front side elevation view thereof;

FIG. 6 is a rear side elevation view thereof;

FIG. 7 is a right side elevation view thereof; and,

FIG. 8 is a left side elevation view thereof.

The broken lines shown in the figures illustrate portions of the suspended lightguide luminaire with linear sound baffles that form no part of the claimed design.

1 Claim, 6 Drawing Sheets
